UNITED STATES PATENT OFFICE.

EDWARD C. ROSS, OF NEWBURG, NEW YORK.

DESIGN FOR A RADIATOR.

SPECIFICATION forming part of Design No. 33,924, dated January 15, 1901.

Application filed December 8, 1900. Serial No. 39,234. Term of patent 14 years.

To all whom it may concern:

Be it known that I, EDWARD C. ROSS, a citizen of the United States, residing at Newburg, in the county of Orange and State of New York, have invented and produced a new and original Design for a Radiator; and I do hereby declare the following to be a full, clear, and exact description of the same, reference being had to the accompanying drawing, which forms a part thereof.

My invention is a new and useful design for a radiator; and it consists in the novel features hereinafter described, reference being had to the accompanying drawing, which represents a side elevation of my design.

My design consists in a radiator having horizontally-disposed end sections, connected by vertical columns, one of said sections having a lateral extension, and an elbow extending toward the other section and away from said columns.

In the drawing, A represents one of the end sections, B the other end section, and C C C the vertical columns connecting the horizontally-disposed sections.

D represents the lateral extension of section A, which extends horizontally, and E represents the elbow, having a part e extending from the extension D toward section B and a part e' extending in a direction away from the columns C C C.

It is obvious that the radiator can be inverted, so as to have the elbow extending upwardly and outwardly from the lower section instead of downwardly and outwardly from the upper section.

What I claim, and desire to secure by Letters Patent, is—

The design for a radiator herein shown and described.

In testimony whereof I affix my signature in presence of two witnesses.

EDWARD C. ROSS.
